UNITED STATES PATENT OFFICE.

CHARLES GILBERT HAWLEY, OF CHICAGO, ILLINOIS, ASSIGNOR TO CENTRIFIX CORPORATION, OF CLEVELAND, OHIO, A CORPORATION OF OHIO.

CENTRIFUGAL DUST CATCHER.

Application filed May 4, 1925. Serial No. 27,836.

My invention relates to means for collecting and removing or abstracting dust from vertical stacks, vents and the like, with particular reference to such improvements in the construction and operation of cupolas and other short stacks, wherein relatively high temperatures are maintained or are attained at intervals. The gases rising in such stacks are usually heavily burdened with dust particles (ash, coke and metal particles). These are lost to the atmosphere, and where the value of the dust is of no account, the dust should nevertheless be removed to avoid annoyance in the surrounding territory.

The invention will be readily understood on reference to the accompanying drawings, in which—

Figure 1 is a vertical section of a centrifugal dust catcher embodying the invention;

Figure 2 is a horizontal section thereof on the line 2—2 of Figure 1;

Figure 3 is a like section on the line 3—3 of Figure 1;

Figure 4 is an enlarged detail taken from the upper part of Figure 1; and

Figures 5, 6, 7 and 8 are detail views having to do with the form and means of suspension of the tuyère blades of the centrifugal element of my invention.

The structure in this application is to be contrasted with those of my copending applications, and it may be at once stated that the special object of this invention is to provide a dust catcher of comparatively light weight and one which shall be made up of few parts, all readily accessible and easy to renew.

In the drawings, the parts 2 and 3 are the upper and lower sections of the chimney, stack or vertical duct through which the dust bearing gases rise. On the top of the part 2 is a light floor section 4. Rising from this is a casing comprising the cylindrical portion 5 and the preferably conical top portion 6. The latter carries the top ring 7 which, in turn, supports the stack section 3. The latter may stop just above the ring 7, but usually extends considerably higher as a measure of bettering the draft of the stack 2. From the top 7 I suspend a ring 8 which at the inside is fixed to the depending end of the stack 3. The part 3 may be the means of suspension or it may be supplemented by a number of hanger

bolts 9. The outer edge of the ring 8 is in the form of ratchet teeth 8' and on the straight section 8'' of each tooth I rivet a short piece of angle iron 10. Obviously the edge of the plate may be turned up, but generally it is easier to provide the raised edge by using a separate angle iron 10.

Some distance below the member 8 I suspend or support a corresponding ratchet disk 11 preferably of somewhat larger diameter than the ring 8. It has corresponding ratchet teeth 11', that is, there are the same number of teeth 11' as teeth 8' in the ring 8, the difference being that they are slightly longer due to the increased diameter. The part 11 is positioned far enough above the top of the stack section 2 to provide ample gas passages 12 at the sides, and it is preferably supported in that position by a plurality of hollow legs 13 which rest on the floor section 4. The tops of these legs register with dust dumping holes 14 at the periphery of the plate 11.

When employed at the top of a cupola or the like, where the temperatures run high, the part 11 is protected by a coating of fire-proof material 15, suspended from the plate by suitable hanger bolts 16.

The centrifugal apparatus is completed by the addition of the tangentially positioned tuyère blades 17, one for each pair of ratchet teeth 8', 11'. Each tuyère blade comprises a flat piece of sheet metal which rests against the upper and lower ratchet teeth of the parts 8 and 11. Each blade is suspended from the top ring 8 and of its own weight rests against the edge of the member 11. Most conveniently the suspension device is a simple hook 17' formed by bending down the top edge of the plate or blade and hooking it over the raised edge 10' on the member 8. Sufficient space 18 is left between the top 10 and the bottom of the ring 7 to permit the blades to be unhooked and taken away and as easily replaced.

Bolts 19, such as are shown in Figure 5, may serve as a substitute for the hooks 17, but are more difficult to install.

By reference each blade 17 is characterized by a strengthening bend 17' and an extended edge 17'', the latter coacting with the next blade to form an inlet tuyère or nozzle 20. Obviously there are as many of these tuyères as there are ratchet teeth and tuyère blades. Thereby I provide a com-

plete tuyère ring (composed of the suspended tuyère blades) which presents a plurality of relatively narrow slit-like tuyères through which the gases must pass to reach

5 the outlet 3' and stack 3.

Attention is called to the difference in diameter between the outlet 3' and the top of the tuyère ring whereby the annular ring or abutment 21 is formed.

10 The parts 22 represent dust disposal down pipes depending from the hollow legs 13, on the exterior of the stack 2. These usually serve to convey the collected dust to a bin or box at the base of the stack 2.

15 The operation of the invention is as follows: The dust carrying gases rising through the stack 2 are deflected by the overhanging centrifugal unit and are distributed in the circumferential space 12. From

20 thence the gases enter the tangential tuyères 20. Immediately these thin tuyère streams or films impact upon the inner sides of adjacent blades and the dust is precipitated thereon. As will be apparent, the entrance

25 of the many tangential streams of rapidly flowing gases results in the organization of a whirling mass of gas within the circumferential wall of tuyère blades. By reason of this rapid rotation the dust is prevented 30 from reaching the axis of the tuyère structure and is more or less rapidly worked down to the bottom 11. Sweeping around the periphery of that part the dust encounters the several holes 14 and falls into the hollow 35 legs 13, there to be disposed of through the

down pipes 22. The removal of the dust in this manner leaves the gases free to press toward the exit and escape through the stack 3.

The overhanging annular surface or abutment 21 successfully prevents the carrying over of dust from the top of the tuyère structure into the outlet 3'.

The structure defined is of such simplicity and low cost and so effective in its operation 45 as to meet extensive needs and be practicable for wide application.

Having thus described my invention, I claim as new and desire to secure by Letters Patent:

1. The herein described apparatus comprising a stack, in combination with a casing at the top thereof, a central outlet at the top of said casing, an upright tangential tuyère comprising tuyère blades suspended from the top of said casing, a suitable tuyère bottom suspended above the top of the stack within the casing, and means for discharging the collected substances from the periphery of said bottom. 55

2. The herein described apparatus comprising a tuyère structure, composed of a top ratchet ring and a ratchet-like bottom, in combination with tuyère blades suspended from the top ring and swinging and resting against the edge of said bottom. 60

In testimony whereof I have hereunto set my hand this 3 day of April, A. D. 1925.

CHARLES GILBERT HAWLEY.
